UNITED STATES PATENT OFFICE.

HARRY G. AINSWORTH, OF KENTLAND, INDIANA.

DOOR CONTROL.

Application filed July 14, 1921. Serial No. 484,727.

To all whom it may concern:

Be it known that I, HARRY G. AINSWORTH, a citizen of the United States, residing at Kentland, in the county of Newton and 5 State of Indiana, have invented certain new and useful Improvements in Door Controls, of which the following is a specification, reference being had to the accompanying drawings, and to the reference characters 10 marked thereon, which form a part of this specification.

This invention relates to electrical means for controlling the opening and closing of doors, and more particularly doors of garages. The invention consists in the devices 15 and combination of devices illustrated and described, and more particularly pointed out in the appended claims.

In the drawings:

20 Fig. 1 is a top plan view of the device, looking down upon the top of the doors.

Fig. 2 is an end elevation of the device, looking toward the doors.

Fig. 3 is a side elevation.

25 Fig. 4 is a central, vertical, sectional view, enlarged, the section being taken on the plane of the dotted line 4—4 of Fig. 1.

Fig. 5 is a perspective view of the traveling blocks used in the device.

30 Referring to the drawings, A represents the walls of a building, such as a garage, and B, B, a pair of doors hinged thereto at b, said doors being shown closed in Fig. 1, in full lines, and shown in dotted lines as 35 open. C is a timber or a suitable fixed support of a building, supporting one end of a pair of spaced guide blocks D, D. In guide ways 1 of the guide blocks D are located movable blocks E, E', each block having

40 cut away ends e adapted to fit and slide within the longitudinal grooves 1. The blocks D are suitably fastened in a casting F upon which is mounted an electric motor M, suitably connected to an electric circuit indicated by the lines 2, 3, 4. The motor 45 shaft is provided with a worm W in mesh with a worm gear G. The motor shaft is horizontally disposed, as shown, and the worm gear shaft vertically disposed.

50 On the lower end of the worm gear shaft g is a sprocket wheel H. Secured to a shaft h, properly journaled in a cross bar h', is a second sprocket wheel H'. A sprocket chain H² is mounted upon the sprocket wheels H, H'. It will be understood that when the motor is operated, the worm W turns the

worm gear G and by means of the sprocket wheels H, H', the sprocket chain H² is moved continuously in one direction. To one of the links I of the sprocket chain H² 60 is secured a downwardly projecting arm I', which arm is adapted to have movable engagement with a transversely arranged groove or recess e¹ in the block E. The under side of the block E is provided with a catch e² and the under side of the block E' is provided with a pivoted locking hook e³. When the hook e³ engages the catch e², the blocks E, E' are securely locked together and travel together back and forth, as the 70 case may be, between the guide blocks D. To the lower end of the block E, is pivotally secured, at 5, one end of a rod R. The other end of the rod R is pivotally secured at 6 to one of the hinged doors. 7 is a push 75 button switch located in the electrical circuit with the circuit closed. When the button 8 is pushed in by the contact point 9, the circuit is broken. The contact point 9 is on one end of a pivoted lever 10. A 80 spring 11 secured at one end to the lever 10 and at the other end to a fixed part, such as the guide bar 10, will tend to normally hold the contact point 9 away from the button 8, as shown in Fig. 1. 12 is an operating rod 85 pivotally connected at its forward end to the lever 10, and at its rear end to a tripping arm 13. The lower end 14 of the tripping arm 13 is adapted to be engaged by the end of a tripping bar 15, which tripping 90 bar is secured to and depends from the lower side of the block E.

16 indicates switches which may be located at any convenient point in the circuit. Assuming the doors to be closed and the 95 parts in the position shown in Fig. 1, the operator closes one of the switches 16. Current flows immediately through the closed switch 7 to the motor, putting the latter in operation. The rotation of the sprocket 100 wheel through the motor, the worm and the worm gear, will push the blocks E' and E downwardly to the position shown in dotted lines in Fig. 1. The pin I' travels in the recess e¹ say to the right hand side (as we 105 look at Fig. 1), until the link of the chain to which said pin I' is attached gets to the other sprocket wheel H'. Then the pin travels to the left of the recess e¹ until it rests in the center position. Meanwhile, 110 the arm 15 has likewise been moved down until it contacts with the lower end of the

lever 10, pushing said lever against the tension of the spring 11 until its contact point 9 pushes the button 8 into the switch 7; thus breaking the circuit. Coincidentally with 5 this, the rods R have moved forward and pushed the doors open.

To close the doors, the reverse movement occurs. The operator closes one of the switches 16, the motor is again put in operation 10, the sprocket wheels are again turned in the same direction and the chain starts moving in the same direction. The pin I' however tends to move back into its original position, and in so doing, moves in the slot 15 e^1 of the sliding block E. As this sliding block E is pulled back by the pin I' it also pulls back the block E' because said block E' and the block E are still locked together at e^2, e^3 . Pulling the block E' back to its 20 original position produces the reverse pull on the rods R and consequently closes the doors B. As soon as the trip arm 15 reaches the position shown in Fig. 3, it trips the arm 14, pushes the rod 12 and the lower end 25 of the lever 10 against the tension of the spring 11, the contact point 9 pushes the button 8 into the switch 7, the circuit is broken and the motor stops.

It will thus be seen that there is manual 30 operation for closing the circuit, automatic movement of the mechanical parts driven by the motor to open the doors or to close the doors, as the case may be, and that the circuit is automatically broken and the movement of the motor stopped whenever the doors are in the full closed or the full open position.

If for any reason it is desired to move the parts manually, without the use of the motor, 40 or if the motor is out of order, a chain J trailed over a pulley 17, connecting with the bell crank lever 18, may be pulled; thus disengaging the locking hook e^3 from the catch e^2 . Thereupon the block E' may be moved 45 by hand and the door opened or closed as the case may be.

I claim as my invention:

1. A device for opening and closing a door, comprising in combination with a hinged door, an electric circuit including a motor, a pair of sprocket wheels one of which is operatively connected to the motor, an endless sprocket chain on said wheels, a fixed support, parallel guide ways secured to said 55 support, a block movable in said guides and operatively connected with a part of the sprocket chain to travel therewith, a bar pivotally connected at one end to said block and at its other end to the hinged door, a 60 switch for closing the circuit and means for automatically breaking the circuit at a predetermined time in the movement of the sprocket chain.

2. A device for opening and closing a 65 door, comprising in combination with a

hinged door, an electric circuit including a motor, a pair of sprocket wheels one of which is operatively connected to the motor, an endless sprocket chain on said wheels, a fixed support, parallel guide ways secured 70 to said support, a block movable in said guides and operatively connected with a part of the sprocket chain to travel therewith, a bar pivotally connected at one end to said block and at its other end to the hinged door, a switch for closing the circuit and means for automatically breaking the circuit at a predetermined time in the movement of the sprocket chain, said 75 means including a normally closed switch 80 in the circuit and a switch opening member.

3. A device of the character described comprising an electric circuit including a motor, a normally closed switch and one or more normally open switches, a hinged door, a pair of guide ways secured to a fixed support, a pair of shafts, a revoluble sprocket wheel on each shaft, a sprocket chain upon said sprocket wheels a block 85 movable between and longitudinally of the guide ways, operative means for actuating said chain from the motor, the block being secured to a part of the chain whereby 90 said block is moved by and travels with the chain, means for automatically stopping the motor when the block has travelled the length of the guide ways in either direction and operative connections between 95 said block and the door.

4. A device of the character described comprising an electric circuit including a motor, a normally closed switch and one or more normally open switches, a hinged door, a pair of fixed guide ways, a pair of shafts, a revoluble sprocket wheel on each shaft, a sprocket chain upon said sprocket wheels a block 100 movable between and longitudinally of the guide ways, operative means for actuating said chain from the motor, operative means on a part of the chain actuating 105 said block by and with the chain, means for automatically stopping the motor when the block has travelled the length of the guide ways in either direction and operative connections between 110 said block and the door, said chain actuating means including a worm on the motor shaft and a worm gear on one of the sprocket wheel shafts.

5. A device of the character described comprising an electric circuit including a motor, a normally closed switch and one or more normally open switches, a hinged door, a pair of fixed guide ways, a pair of shafts, a revoluble sprocket wheel on each shaft, a sprocket chain upon said sprocket 120 wheels a block movable between and longitudinally of the guide ways operative means for actuating said chain from the motor, operative means for actuating said block by 125 130

- the movement of the chain, means for automatically stopping the motor when the block has travelled the length of the guide ways in either direction and operative connections between said blocks and the door, said automatic stopping means including a contact arm at one end of the guide ways for opening the normally closed switch, a lever connected thereto, a lever at the opposite end of the guide ways, a rod connected with each lever and a detent connected with and travelling with the sprocket wheel adapted to contact with said levers.
6. A device of the character described comprising an electric circuit including a motor, a normally closed switch and one or more normally open switches, a hinged door, a pair of fixed guide ways, a pair of shafts, a revoluble sprocket wheel on each shaft, a sprocket chain upon said sprocket wheels a pair of blocks movable between and longitudinally of the guide ways operative means for actuating said chain from the motor, operative means for actuating said block by the movement of the chain, means for automatically stopping the motor when the block has travelled the length of the guide ways in either direction and operative connections between said block and the door, one of said blocks being operatively secured to a part of the sprocket chain and travelling therewith and means for locking said blocks together.
7. A device of the character described comprising an electric circuit including a motor, a switch and a normally closed switch, a hinged door, a push and pull rod pivotally connected at one end to said door and operative connections between the other end of the rod and the motor for actuating the rod, said connections including a sprocket chain, a transversely slotted movable block, and a pin on the chain movable in said slotted block.

In testimony that I claim the foregoing as my invention I affix my signature, in the presence of two witnesses, this 9th day of July, 1921.

HARRY G. AINSWORTH.
